COMBINED RADIO AND MOTION-PICTURE PROJECTOR OR SIMILAR ARTICLE

Antoine Jean Merles, Paris, France, assignor to
Societe D'Applications Radio-Electriques A
L'Aeronautique Et La Marine S. A. R. A. M.,
Asnieres, France, a society of France

Application November 17, 1947, Serial No. 142,593
In France May 20, 1947

Term of patent 14 years

(Cl. D56—4)

To all whom it may concern:

Be it known that I, Antoine Jean Merles, a citizen of the French Republic, residing at Paris (Seine) France, 34 quai de Passy, have invented a new, original, and ornamental Design for a Combined Radio and Motion-Picture Projector or Similar Article, of which the following is a specification, reference being had to the accompanying drawings, forming part thereof.

Fig. 1 is a front perspective view of a combined radio and motion-picture projector cabinet showing my new design, the side doors being closed, and

Figs. 2 and 3 are opposite perspective views showing the device as it appears from angles somewhat different from that of Fig. 1, the right

hand door on Fig. 2 and the left hand door on Fig. 3 being shown in open position.

The rear of the cabinet is plain.

I claim:

The ornamental design for a combined radio and motion-picture projector or similar article, as shown and described.

ANTOINE JEAN MERLES.
